TAPER HOLDER AND SNUFFER

Elizabeth D. Muzzy, San Francisco, Calif.

Application November 9, 1946, Serial No. 708,913

1 Claim. (Cl. 67—6)

1

This invention relates to taper holders and snuffers. In Catholic cathedrals and churches, shrines are set up and dedicated to saints and holy names. Before each shrine an altar light burns, consisting of a cup of oil with a lighted wick floating therein.

Devotees offering prayers and invocations before these shrines obtain candles or tapers, which they light by inserting the ends into the cup until ignited by the burning light therein. When tapers are used, they are lighted then immediately extinguished by blowing them out and laying them in a bowl provided therefor.

Such tapers are a serious fire hazard, because the flame in the cup must be lower than the top edge to keep it burning in drafts and when atmospheric disturbance caused by passing persons and other causes occur.

This necessitates inserting the end of the taper downward into the cup at a relatively acute angle, often resulting in the flame shooting up the length of the taper. In the hands of a nervous person the taper is apt to be dropped on the carpet, or set fire to the clothing of the user. Furthermore, the flame may be too great to be extinguished by blowing it out; especially in the hands of elderly or invalid devotees.

Among the objects of the invention is the provision of protective means for enclosing the length of the taper within a tube.

Another object is the provision of a means for exposing only the end of the taper for ignition, and its withdrawal into the tube for extinguishment.

A further object is the use of a material in the tube that will absorb heat and extinguish the flame when it contacts the end of the tube.

Other objects and advantages will appear as the description proceeds. In the specification and the accompanying drawings the invention is disclosed in its preferred form. But it is to be understood that it is not limited to this form, because it may be embodied in modifications within the spirit of the invention as defined in the claim following the description.

In the one sheet of drawings:

Fig. 1 is an enlarged side elevation of a taper holder and snuffer constructed in accordance with this invention.

Fig. 2 is a plan view from above, of the same.

Fig. 3 is a further enlarged detail in vertical section on the line III—III, Fig. 1.

Fig. 4 shows a modified form of taper holder in isometrical perspective.

2

In detail the structure shown in Fig. 1, comprises the tubular body 1, preferably composed of aluminum alloy of the required stiffness. It has the vertical flanges 2, 3 integral with the body which extend longitudinally separated, from each other, above said body.

The rearward ends of these flanges are bent to form the inwardly extended opposed stops 4, 5, Fig. 2, overhanging the width of the slot 6 between the flanges. The forward end of the body beyond the ends of the flanges is die formed into a tapered nose 7.

The taper control consists of the tubular socket 8 snugly fitting the inner end of the taper 9 and freely slideable within the body 1. It has the upwardly extending sides 10, 11 between the flanges 2, 3, that are bent laterally to form the concave thumb top. This upper surface is knurled to give better frictional contact with the thumb, should it become coated by wax from the tapers among which it may be laid.

This invention operates substantially as follows: The end of the taper 9 is pushed into either end of the socket 8 where it becomes frictionally held. The outer end of the taper is then thrust into the rearward end of the body, until the sides 10, 11 of the socket 8 encounter the stops 4, 5, which yield laterally and pass the socket into the body 1, and prevent it falling out of the body when picked up.

The conventional tapers are marketed in about sixteen inch lengths for candle lighters. The present device is made to enclose about one third the length of the standard taper, for economy, and convenience in handling.

The loaded holder is grasped in the hand with the thumb resting in the concave top of the slide, which is then pushed forward until the forward taper end 12 protrudes and may be lighted in the altar cup as above described.

The burning taper is extinguished by moving the socket backward until the end 12 of the taper enters the nose 7. The thermal efficiency of aluminum is such that the flame is extinguished instantly upon contact with the metal, even before it enters the nose 7. However, other metals and materials will extinguish the flame by smothering it within the body 1.

When the socket reaches the top at the inner end of the nose at 13 and the taper has been consumed, the socket is withdrawn and the unburned end of the taper which is the length of the nose 7, provides means for easy removal of the taper from the socket 8 for a reload.

While it is preferable to taper the end 7 as

shown, it will function satisfactorily in the cylindrical contour of the body 1.

The modified socket shown in Fig. 4, is formed of relatively thin spring material so that the socket 8x will normally open to receive the end of a taper that may become tufted or enlarged. The frayed or tufted end is laid into the socket and the sides 10x, 11x are pinched together and passed into the rear end of the body at 4, 5, as described. This modification is equally effective 10 and cheaper to produce. The outward friction of the sides 10x, 11x, holds the socket in adjusted position between the flanges 2, 3.

Having fully described this invention and its mode of operation, what I claim and desire to 15 secure by Letters Patent is:

A taper holder and snuffer comprising a tubular body having a tapered nose portion and longitudinal flanges forming a slot in said body from

said nose portion to the opposite end of said body, the rear corners of said flanges overhanging and forming a yielding stop across said slot; and a 5 taper holding socket slidable in said body and having side portions extending outward between said flanges and forming a manual control for said taper holding socket.
